(57) **CLAIM**

The ornamental design for a motorcycle fairing adjustment member, as shown and described.

DESCRIPTION

FIG. 1 is a front perspective view of a motorcycle fairing adjustment member bearing the claimed design;

FIG. 2 is a front elevation view of a motorcycle fairing adjustment member bearing the claimed design;

FIG. 3 is a rear elevation view of a motorcycle fairing adjustment member bearing the claimed design;

FIG. 4 is a left side elevation view of a motorcycle fairing adjustment member bearing the claimed design;

FIG. 5 is a right side elevation view of a motorcycle fairing adjustment member bearing the claimed design;

FIG. 6 is a top plan view of a motorcycle fairing adjustment member bearing the claimed design;

FIG. 7 is a bottom plan view of a motorcycle fairing adjustment member bearing the claimed design;

FIG. 8 is a right side elevation view of a motorcycle fairing adjustment member bearing the claimed design;

FIG. 9 is a front perspective view of another embodiment of a motorcycle fairing adjustment member bearing the claimed design;

FIG. 10 is a front elevation view of the motorcycle fairing adjustment member of FIG. 9;

FIG. 11 is a rear elevation view of the motorcycle fairing adjustment member of FIG. 9;

FIG. 12 is a left side elevation view of the motorcycle fairing adjustment member of FIG. 9;

FIG. 13 is a right side elevation view of the motorcycle fairing adjustment member of FIG. 9;

FIG. 14 is a top plan view of the motorcycle fairing adjustment member of FIG. 9;

FIG. 15 is a bottom plan view of the motorcycle fairing adjustment member of FIG. 9;

FIG. 16 is a front perspective view of another embodiment of a motorcycle fairing adjustment member bearing the claimed design;

FIG. 17 is a front elevation view of the motorcycle fairing adjustment member of FIG. 16;

FIG. 18 is a rear elevation view of the motorcycle fairing adjustment member of FIG. 16;

FIG. 19 is a left side elevation view of the motorcycle fairing adjustment member of FIG. 16;

FIG. 20 is a right side elevation view of the motorcycle fairing adjustment member of FIG. 16;

FIG. 21 is a top plan view of the motorcycle fairing adjustment member of FIG. 16;

FIG. 22 is a bottom plan view of the motorcycle fairing adjustment member of FIG. 16; and,

FIG. 23 is a right side elevation view of the motorcycle fairing adjustment member of FIG. 16.
